UNITED STATES PATENT OFFICE.

JAMES B. RHODES, OF GRAND RAPIDS, MICHIGAN.

PRUNING-SHEARS.

SPECIFICATION forming part of Letters Patent No. 729,894, dated June 2, 1903.

Application filed August 23, 1902. Serial No. 120,783. (No model.)

To all whom it may concern:

Be it known that I, JAMES B. RHODES, a citizen of the United States, residing at Grand Rapids, in the county of Kent and State of Michigan, have invented certain new and useful Improvements in Pruning-Shears; and I do hereby declare the following to be a full, clear, and exact description of the invention, such as will enable others skilled in the art to which it appertains to make and use the same.

My invention relates to improvements in pruning-shears; and its object is to provide means whereby two shear-blades having oppositely-inclined chisel edges may be operated successfully. Heretofore all attempts to utilize such shear-blades in making heavy cuts has resulted in springing the blades toward each other to such an extent that they would override and cut into each other, and thus be rendered useless.

My invention consists in providing such blades with inwardly-projecting extensions at their outer ends adapted to overlap each other as the blades are closed upon the object to be cut and before the cutting has progressed far enough to spring the blades, and thus operate as guides to hold the blades from springing inward toward each other, as will more fully appear by reference to the accompanying drawings, in which—

Figure 1 is a side elevation of a device embodying my invention with the blades opened. Fig. 2 is the same with the blades closed. Fig. 3 is the same viewed at right angles to Fig. 2, and Fig. 4 is a transverse section on the line 4-4 of Fig. 2 looking toward the overlapping ends of the blades.

A represents a pair of short stout shear-blades of the usual construction and having oppositely-inclined chisel edges B, said blades being pivoted to each other at C and provided with handles D. So far the device is of well-known construction; and my invention consists in the addition to the outer ends of these blades A, consisting of the inwardly-projecting extensions E, having rounded sur-

faces and not adapted to act as cutters, but intended to overlap and engage each other before the operation of cutting has progressed sufficiently to spring the blades toward each other. These extensions thus serve as guides for the outer ends of the blades and by slidably engaging each other support the ends of the blades against the lateral strain due to the action of the chisel edges of the same, and thus prevent these edges from overlapping and damaging each other. These end extensions E also serve to engage any object of such size that the blades would be opened so wide as to have a tendency to slide endwise when closed upon the same. They thus perform the incidental function of holding the blades from slipping endwise upon the object operated upon.

Having thus fully described my invention, what I claim, and desire to secure by Letters Patent, is—

1. In combination with shear-blades, inwardly-projecting extensions on the ends of the blades, adapted to overlap and slidably engage each other, and prevent the blades from springing toward each other.

2. In combination with shear-blades having oppositely-inclined, chisel edges, inwardly-projecting extensions on said blades, adapted to overlap and slidably engage each other, and prevent springing of the blades toward each other.

3. In combination with shear-blades having oppositely-inclined, chisel edges, inwardly-projecting extensions on the ends of the blades, and having rounded non-cutting surfaces, and also adapted to overlap and slidably engage each other to prevent lateral springing of the blades toward each other.

In testimony whereof I affix my signature in presence of two witnesses.

JAMES B. RHODES.
